A. J. GURNEY

WIRE HANGER

Filed Jan. 13, 1925

Fig. 2.

Inventor

A. J. Gurney.

By

Lacy Gurney, Attorney

UNITED STATES PATENT OFFICE.

ALBERT J. GURNEY, OF CANTON, OHIO, ASSIGNOR TO THE AMERICAN MINE DOOR CO., OF CANTON, OHIO, A CORPORATION OF OHIO.

WIRE HANGER.

Application filed January 13, 1925. Serial No. 2,227.

This invention relates to an improved hanger for trolley wires or the like, and seeks, among other objects, to provide a simple and efficient device of this character which will embody but few parts, but nevertheless, will be capable of rigidly gripping a trolley wire and suspending the wire in position.

The invention further seeks to provide a hanger incorporating a pair of coacting jaws, and wherein novel means will be provided for wedging the jaws together into engagement with a wire.

And the invention seeks, as a still further object, to provide a hanger wherein the jaws will be relatively shiftable endwise for drawing the jaws together, and wherein simple means will be provided for adjustably shifting the jaws.

Other and incidental objects will appear hereinafter.

In the accompanying drawings:

Figure 1 is a side elevation of my improved hanger,

Figure 2 is a horizontal sectional view on the line 2—2 of Figure 1, looking downwardly.

Figure 3 is a vertical sectional view on the 3—3 of Figure 1, looking in the direction indicated by the arrows.

Figure 4 is a vertical sectional view similar to Figure 3, but showing the use of a cotter pin for locking the jaws together.

In carrying the invention into effect, I employ a pair of oblong jaws 10 and 11 which are grooved at their lower margins, as indicated at 12, to engage a trolley wire as conventionally illustrated at 13. Above the grooves 12, the jaws are hollow and closing the jaws at the ends thereof are mating end walls 14. As brought out in Figure 2, the end walls, at each end of the hanger, incline in opposite directions while the forward end wall of the jaw 11 is thickened, and formed in said end wall from the inner vertical edge thereof is a transverse opening or notch 15. Rising from the jaw 10 is a medially disposed sleeve 16 which overhangs the jaw 11 and is internally threaded to accommodate the stud 17 of a conventional insulator so that the hanger may thus be readily mounted in position for use. As will be observed, the jaw 11 is formed at its upper side with a semi-circular portion 18

which is provided with a flat upper face to fit beneath the sleeve 16.

Formed in the side wall of the jaw 10 is a medial opening 19 and formed in the side wall of the jaw 11 is a like registering opening 20. At the rear end of the opening 19 the jaw 10 is provided with a transverse reinforcing web 21 and integrally formed on said web is an internally threaded conical sleeve 22 extending horizontally toward the forward end of the jaw but inclined toward its forward end away from the side wall of the jaw. Near its forward extremity the sleeve is, as particularly shown in Figure 2, provided with a transverse opening 23. Formed on the jaw 11 to cooperate with the sleeve 22 is an inwardly directed loop 24 integrally connected with the jaw above and below the opening 20 so that the loop is thus disposed opposite said opening. The loop is shaped to extend behind the sleeve 22 and, as brought out in Figure 2, is provided at the bight thereof with a beveled inner face to coact with the longitudinally inclined wall of the sleeve. Extending freely through the opening 15 in the forward end wall of the jaw 11 is a cap bolt 25 screwed into the said sleeve. Thus, as will be appreciated, the bolt may be adjusted for shifting the jaw 11 endwise relative to the jaw 10, when the loop 24 will ride downwardly along the sleeve 22 for wedging the jaws together and tightly binding said jaws in engagement with the trolley wire 13. On the contrary, by removing the bolt, the jaws may be relatively shifted endwise in the opposite direction and disengaged from the trolley wire. Accordingly, the hanger may be easily and quickly applied or removed.

In use, the sleeve 16 of the jaw 10 is first screwed on the insulator stud 17 for rigidly mounting said jaw, when the jaw 11 is assembled with the jaw 10 and the loop 24 of the latter jaw engaged over the sleeve 22, the trolley wire being, of course, disposed between the lower margins of the jaws. The bolt 25 is then inserted through the opening 15 and screwed into the sleeve 22 for shifting the jaw 11 longitudinally relative to the jaw 10 and wedging the jaws into engagement with the wire. I accordingly provide a particularly simple and efficient device for the purpose set forth and, as will be seen, a hanger which comprises but

squarely against the inner or bottom wall of the said socket. The operator then uses a hammer, striking the outer plug in the direction of the length of the axle whereby the wheel is jarred loose from the axle and the key thereof and may be quickly removed.

Having described the invention what is claimed is—

A device adapted to be used for removing a wheel from an axle upon which it is keyed comprising a body provided at its opposite ends with alined sockets of different sizes, and anvil plugs fitting in the sockets.

In testimony whereof I affix my signature.

CASH A. CLEMONS.

coact with the clamping means of the other jaw for drawing the jaws toward each other into engagement with a wire as the jaws are shifted.

- 5 16. A hanger of the character described including companion relatively shiftable wire engaging jaws each having clamping means lying between the jaws and the clamping means of each jaw being formed to coact with the clamping means of the other jaw for drawing the jaws toward each other into engagement with a wire as the jaws are shifted, and means to coact with one of said first mentioned means for shifting the jaws.
- 10 17. A hanger of the character described including companion relatively shiftable wire engaging jaws one provided with an inclined portion and the other provided with a portion to coact with said inclined portion for wedging the jaws into engagement with a wire as the jaws are shifted, said portions of the jaws lying between the jaws.

- 15 18. A hanger of the character described including companion relatively shiftable wire engaging jaws one provided with an inclined portion and the other provided with a loop to embrace said inclined portion coacting therewith for wedging the jaws toward each other in engagement with a wire as the jaws are shifted, said portion of the

former jaw and said loop of the latter jaw being disposed between the jaws.

19. A hanger of the character described including companion relatively shiftable wire engaging jaws each having clamping means and the clamping means of each jaw being formed to coact with the clamping means of the other jaw for drawing the jaws toward each other in engagement with a wire as the jaws are shifted, said means being housed between the jaws.

20. A hanger of the character described including companion relatively shiftable wire engaging jaws having housed coacting means for drawing the jaws toward each other in engagement with a wire as the jaws are shifted, said means being carried by the jaws respectively.

25 21. A hanger of the character described including companion relatively shiftable wire engaging jaws having housed coacting means for drawing the jaws toward each other in engagement with a wire as the jaws are shifted, said means being carried by the jaws respectively, and means to coact with one of said first mentioned means for shifting the jaws.

In testimony whereof I affix my signature.

ALBERT J. GURNEY. [L. s.]
